UNITED STATES PATENT OFFICE

CHARLES NESSLER, OF NEW YORK, N. Y., ASSIGNOR TO THE NESTLE-LE MUR COMPANY, OF NEW YORK, N. Y., A CORPORATION OF OHIO

MEANS FOR TESTING HAIR PREPARATORY TO TREATING OR WAVING THE SAME

Application filed December 4, 1925. Serial No. 73,088.

This invention relates generally to the art of permanent hair waving and more particularly to means for testing growing hair preliminary to a waving operation of the hair on the head in order to properly adapt the waving operation thereto.

The art of permanent hair waving on the head of the subject includes the winding of strands of hair about curling rods, treating the wound strands with an alkaline solution, and in heating the strands to a given temperature for a definite period of time. In the practice of the art it has been found that hair undergoing treatment by the process outlined is variously affected, the finer and softer grades of hair being seriously injured by the action of an alkaline solution having a strength suitable for use with coarser and more resistant grades of hair.

In order to overcome this objectionable characteristic of the prior hair waving practice, a process has been developed in which alkaline solutions of different strengths are employed in order to treat the different grades of hair with solutions having a strength or concentration appropriate to the grade of the hair under treatment.

A general object of the present invention is to provide means which will authoritatively measure the quality or grade of the hair under consideration for treatment, so that the strength or concentration of the lotion appropriate to that particular quality of hair is invariably indicated without chance of error.

In the course of a series of experiments conducted for the purpose of the invention I have found that the quality of the hair can be definitely ascertained by submitting it to tests for elasticity and elongation under a predetermined degree of pull. In order to achieve this useful result, I have devised an apparatus by which tests of the elasticity and capacity for elongation of sample strands of the hair under consideration can

be made. The apparatus includes means for subjecting a given quantity of the sample hair to a measured tensile pull which is preferably the same for all the strands tested. Means are provided for measuring the elongation or stretch produced by the tensile pull referred to, the scale readings which represent the elongation, together with the time and completeness of the reaction of different strands of hair when the weight is removed, being utilized to establish a series of gradations corresponding respectively to a scale of concentration values in the alkaline lotions employed.

I may also employ as an additional factor in performing the tests the element of time as used in the production of a predetermined amount of elongation in the strand, thereby giving the length of stretch a constant value.

Other features of the invention will be hereinafter referred to.

In the drawings, in which a preferred embodiment of the invention has been selected for illustration,

Figure 1 is a view in side elevation of a hair-testing device embodying the invention.

Figure 2 is a view in side elevation and on an enlarged scale of a portion of the device shown in Figure 1.

Figure 3 is a view partly in side elevation and partly in section showing another portion of the device shown in Figure 1.

Figure 4 is a view partly in plan and partly in horizontal section of the parts shown in Figure 2.

Figure 5 is a view in side elevation and on an enlarged scale of a portion of the device shown in Figure 1.

Figure 6 is a view partly in plan and partly in horizontal section of a detail of the device shown in Figure 1.

Figure 7 is a view in vertical section and on an enlarged scale of the clamping device shown in Figure 1.

Figure 8 is a view in vertical section taken on the line 8—8 of Figure 3.

Figure 9 is a view in vertical section taken on the line 9—9 of Figure 3.

Figure 10 is a plan view showing a detail of the construction shown in Figure 3.

Figure 11 is a view in horizontal section taken on the line 11—11 of Figure 2.

Referring to the drawings for a more detailed description of the invention, a hair-testing apparatus is shown in Figure 1 which includes a pair of clamping members 10 and 11 between which a sample strand of hair having a measured quantity of hair contained therein is clamped in order to have a stretching force applied thereto to produce an elongation or stretching of the hair sample.

The stretching referred to is produced through the action of a weight member 13 which is adapted to be moved along the scale beam 14 to thereby apply pressure through a link member 15 to an arm 16 pivoted at 17 on a standard 18. The other end of the arm 16 terminates in the clamping member 10 already referred to and it will be seen that the upward movement of the clamp 10 which is produced by the action of the weight 13 on the scale beam 14 produces the stretching or elongation referred to.

In order to measure the amount of elongation or stretch that is produced in the sample of hair under consideration, a pointer 19 is provided which has a connection at one end with the clamp-carrying arm 16 and which is pivoted at 20 on a vertical frame member 21. The outer or free end of the pointer 19 is arranged to move along a graduated scale 22 to thereby indicate the amount of elongation of the strand of hair which is being subjected to the stretching action.

In order to produce a balanced condition of the parts a secondary weight member 23 is preferably provided, the weight being carried on the arm 16 at the right-hand side of the pivot 17 thereof.

With this arrangement it will be seen that if a strand of hair is clamped between the members 10 and 11 and the weight member 13 moved along the scale beam 14 to a predetermined position thereon, the strand of hair will be stretched or elongated and the amount of stretch or elongation will be shown on the scale 22 for comparison with other strands or known standards.

As a preliminary to the placing of the strand of hair in the clamp members 10 and 11 a portion of the strand is placed in a measuring slot 24 provided in a plate 25. A pointer 26 hinged at 27 is arranged to engage the mass of hair in the slot 24 and to measure the quantity thereof by the position of the forward end of the pointer 26 with a scale 28 so that a like quantity of hair will be invariably selected for subjection to the test. It will thus be seen that by the use of a predetermined

weight applied to a fixed quantity of hair the only variable factor remaining is the length of elongation or stretch which is shown on the scale 22. It will be seen that the quantity of hair measured in the slot 24 is independent of the number of individual hairs in the strand, the quantity of hair being always the same.

In order to facilitate the production of constant or uniform conditions in the testing operations the strand, just previous to the testing operation, is placed in an alkaline solution having a given strength and heated to the boiling point, in order not only to soften the structure somewhat to assist in the measuring operation, but also to establish a constant, uniform temperature in the strand at the time when the test is made. Preferably a heating pad 50, adapted to be dipped into the hot solution, is applied to the strand to retain the heat during the stretching operation. It will be seen that another constant factor is thereby established in the operation so that the variable factor, that is the amount of elongation or stretch is the only factor necessary to be considered in making the test.

It has been found that the making of the tests is facilitated by twisting the strand before applying the stretching process thereto. This is accomplished by attaching the lower end of the strand of hair to be tested to a clamp 29 mounted for vertical movement in a sleeve 30 and normally held in its lower-most position therein through the action of a spring not shown.

In order to bring about a twisting operation on the strand of hair a hand-crank 31 is provided which has a bevel gear connection at 32 with a shaft 33 on which the sleeve 30 is carried so that rotation of the sleeve 30 and the contained clamp 29 produces a twist in the strand of hair as is clearly shown in Figure 2 of the drawings. In order to provide for the contraction in the length of the strand which is produced by the twisting operation, the clamp 29 to which the end of the strand is attached is permitted to rise in the sleeve 30 against the pressure of the spring referred to, a pin 34 carried by a plunger portion of the clamp 29 moving in the slot 35 for the purpose. The degree of twist given the strand of hair is predetermined and is shown on a numbered disk 36 carried by the shaft 33 and cooperating with a stop 37 so that the extent of rotation of the strand can be determined and made uniform in each case.

When the strand has been twisted to the desired extent the clamp 11 is tightened to thereby grasp the twisted strand 38. The weight member 13 is then moved along the beam 14 to the predetermined point whereupon the elongation of the twisted strand 38 is produced and the extent of elongation measured on the scale 22.

The movement of the weight 13 along the

beam 14 is preferably accomplished through operating mechanism best shown in Figure 3 of the drawings. A weight-moving chain 39 is driven by a sprocket wheel 40 carried by the upright frame member 41 and over an idle sprocket member 42 at its other end which is mounted on the forward end of the beam 14. The shaft 43 of the sprocket 40 carries a gear wheel 53 with which a pinion 44 is in mesh, 10 the shaft of the pinion being provided with a crank handle 45 by which the chain 39 is driven. A carriage 46 is provided with rollers 47 which engage the beam 14, the carriage supporting the weight 13 through a suspension member 48. It will thus be seen that rotation of the hand crank 45 results in the movement of the weight member 13 along the beam 14.

With the apparatus described it will be seen that it is a simple matter to establish the elasticity and, to a certain extent, the tensile strength of the strand of hair under consideration. In addition to the factors named, that is, the constancy of the weight used in providing the pull, the uniformity of the quantity of material measured both in length and diameter of the strand, and the remaining variable factor, the elongation of the strand, provide results which are measures of the elasticity of the hair and which provide a direct indication of the strength or concentration of the alkaline solution used in the hair-waving operation.

Other factors may also be usefully employed, for instance, the element of time may be considered in its relation to the reaction of the stretched strand when released from its elongated position and also in measuring the time used in producing the elongation under the tensile pull.

In order to invariably make use of strands containing the same quantity of hair the plate 25 which is provided with the measuring notch 24 is loosely mounted to yield slightly under the drawing action of the hair when pulled through the slot in the event that more hair is present in the measuring slot than is required for the purpose. The withdrawal of a small number of individual hairs is usually enough to restore the balance and to permit the withdrawal of the strand without movement of the plate. When this precise point has been reached the quantity of hair present is correct for the purpose and the strand is then prepared for the testing operation.

While I have hereinabove referred to softening the hair strand by the use of hot alkaline solution, I have also used other softening agents such as chemicals or other agents which have a softening effect on the hair structure, and with or without the accompanying use of heat. For this purpose, I have used with good results, lotions prepared from

water and alkaline salts belonging to the sodium class.

In regard to the twisted condition of the clamped hair strand, this feature of the invention causes all of the hairs to be uniformly stretched so that none of them escape the tensile pulling action thereby insuring the uniformity of the stretching factor. When the hair strand is not twisted, care must be taken to have the clamps securely grip the straight strand in such manner as to leave none of the hairs free, otherwise, the quantity factor may not be maintained.

I wish to observe that the language and expressions which have been employed throughout the specification are used as terms of description only and not of limitation, and such terms are intended to include all the equivalents and such modifications as are possible to be employed within the scope of the invention claimed.

What I claim is:—

1. In a device for testing the stretch of growing hair preparatory to treatment or permanent waving thereof and to determine therefrom the strength of the hair-treating substance best applicable thereto, a scale-beam and a weight movable thereon, means for positively shifting the weight to predetermined position on the scale, a pair of spaced apart clamps for gripping the hair-strand at points a given distance apart, one of said clamps being stationary, means providing intermediate connections between the other clamp and the scale-beam and responding to the movements of the beam and serving to stretch the gripped hair-strand with a given tensile force the strength or amount of which force is determined by the predetermined position to which the weight is shifted on the scale-beam, and means for measuring the stretch of the hair-strand to grade it for treatment of the sampled hair, means providing intermediate connections between the measuring means and the scale-beam whereby the measuring means may be actuated by the movement of the beam.

2. In a device for testing the stretch of growing hair preparatory to treatment or permanent waving thereof and to determine therefrom the strength of the hair-treating substance best applicable thereto, a pivotally mounted arm having its pivotal axis between its ends, a clamp mounted on said arm for engaging one point of the sample strand of the hair, a fixed clamp for engaging another point of said hair strand a given distance from said first mentioned point, a scale-beam having a connecting member pivotally connected to said arm, a positively actuated weight traveling on said scale beam and shiftable to a predetermined position to exert a given amount of tensile pull whereby to swing said arm and thereby stretch said hair-strand, and means connected with and

- actuated by said pivoted-arm for measuring the elongation of said strand to grade it for treatment of the sampled hair.
3. In a device for testing the stretch of growing hair preparatory to treatment or permanent waving thereof and to determine therefrom the strength of hair-treating substance best applicable thereto, a movable clamping member for a strand of the hair, twisting means for engaging another portion of the strand to twist the same, a fixed clamping member for engaging another portion of the twisted strand, means for moving the movable clamping member to stretch the strand, and means for measuring the elongation of the strand.
4. In a device for stretching an object, a pair of clamps for gripping the object at spaced apart points thereof, one of said clamps being movable and the other stationary with respect to the movable one, means for exerting tensile force upon the movable clamp to stretch the gripped object, a rotary-clamp disposed beyond said stationary clamp for gripping and twisting said object while held in said movable clamp but before it is gripped by said stationary clamp, said rotary clamp being provided with a rotative shaft to turn the clamp on its axis and thereby twist the gripped object before stretching it, means for turning the shaft, numbered means connected with and actuated by said shaft and serving to indicate the number of turns thereof, and means for preventing the shaft from turning backwardly during the twisting operation.
5. In a device for testing the stretch of growing hair preparatory to treatment or permanent waving thereof and to determine therefrom the strength of hair-treating substance best applicable thereto, a scale-beam, a weight adapted to be moved along said beam, a pivoted arm having its pivotal axis located between its ends, a link pivoted at one end to said scale-beam and at the other end to said pivoted-arm, a counter-weight carried by said arm at the other side of its pivotal axis from where the link is pivoted, a clamp mounted on the counter-weighted end of said arm for gripping the hair-strand at one point, a graduated-scale for indicating the extent of stretch, an index-member connected with and moved by said arm and cooperating with said graduated-scale, and a stationary clamp for gripping said hair-strand at another point, whereby the hair-strand may be stretched by movement of said pivoted-arm.
6. In a device for testing the stretch of growing hair preparatory to treatment or permanent waving thereof and to determine therefrom the strength of hair-treating substance best applicable thereto, means for stretching a measured quantity of the hair to be treated with a given strength of pull, heated means placed around said hair during the stretching operation, and means for measuring the extent of elongation of the hair to grade it for appropriate treatment of the sample-hair.
7. In a device for testing the stretch of growing hair preparatory to treatment or permanent waving of the same and to determine therefrom the strength of hair-treating substance best applicable thereto, a scale-beam and weight therefor, a rocking-arm having a connecting member pivotally connected with said scale-beam, a hair-strand clamp arranged at a fixed point, a second hair-strand clamp connected with said rocking-arm and moving therewith and coacting with said fixed clamp to stretch the hair-strand, a measuring scale and an index member cooperating therewith and actuated by said rocking-arm to record the amount of stretch.
8. In a device for testing the stretch of growing hair preparatory to treatment or permanent waving thereof and to determine therefrom the strength of the hair-treating substance best applicable thereto, a scale-beam pivoted near one end and a traveling weight mounted thereon, a rocking-arm having a pivoted member operatively connected with said scale-beam at its free end, a hair-strand clamp disposed at a fixed point and a second hair-strand clamp connected with and moved by said rocking-arm to stretch the clamped hair-strand, a stretch indicating scale and an index member connected with and actuated by said rocking-arm and cooperating with said scale.
9. In a device for testing the stretch of growing hair preparatory to treatment or permanent waving thereof and to determine therefrom the strength of hair-treating substance best applicable thereto, a scale-beam provided with a weight, a rotatable shaft on which said beam is mounted, a chain-sprocket and a gear-wheel secured to said shaft, an idle sprocket mounted on said scale-beam and spaced from said shaft, a drive-chain engaging said idle-sprocket and chain-sprocket and connected with and driving said weight along the scale-beam, a driving-pinion meshing with said gear-wheel, a fixed hair-strand clamp, a movably mounted hair-strand clamp having a connecting-member pivotally connected with and actuated by the scale-beam to stretch the clamped hair-strand, and means for measuring the amount of stretch effected by the action of the scale-beam.
10. In a device for testing the stretch of growing hair preparatory to treatment or permanent waving thereof and to determine therefrom the strength of hair treating substance best applicable thereto, a scale-beam pivoted at one end and an adjustable weight mounted thereon, an arm pivoted remotely

from its ends, a link pivoted between the free end of said scale-beam and one end of the arm, a counter-weight carried by said arm at the other side of the pivot, means carried by
5 the counter-weighted end of the arm for gripping a sample hair strand at one point, means fixed in position for gripping the sample at another point whereby the hair may be stretched by movement of said arm, and
10 means for measuring the stretch of the strand to grade it for treatment of the sampled hair.

In testimony whereof, I have hereunto set
my hand.

11 CHARLES NESSLER.
